UNITED STATES PATENT OFFICE.

O. BEECHER, OF CAMDEN, NEW JERSEY, AND R. E. ROGERS, OF PHIA, PENNSYLVANIA.

IMPROVEMENT IN RAILROAD JOURNAL-BOXES.

Specification forming part of Letters Patent No. 40,810, dated December 8, 1863.

To all whom it may concern:

Be it known that we, ORSON BEECHER, of Camden, New Jersey, and ROBERT E. ROGERS, of Philadelphia, Pennsylvania, have invented certain Improvements in Journal-Boxes, Journals, and Car-Wheels; and we do hereby declare the following to be a full, clear, and exact description of the same, reference being had to the accompanying drawings, and to the letters of reference marked thereon.

Our invention consists, first, in an oiling-roller, a frame, and a weighted lever or its equivalent, arranged within a journal-box, substantially as described hereinafter, so as to cause the said roller to deposit a uniform supply of oil on the journal without the aid of springs; secondly, in a partition so arranged within the box as to prevent an undue waste of oil; thirdly, in an annular flange or its equivalent attached to or forming a part of the car wheel or axle for restoring superfluous oil to the oil-chamber of the box; and, fourthly, in an annular flange attached to or forming part of the car wheel or axle for preventing sand, dust, &c., from gaining access to the interior of the box.

In order to enable others to make and use our invention, we will now proceed to describe its construction and operation.

On reference to the accompanying drawings, which form a part of this specification, Figure 1 is a vertical section of a journal-box, journal, and part of a car-wheel constructed according to our improvements; Fig. 2, a transverse section on the line 1 2, Fig. 1; and Fig. 3, a sectional plan of the journal-box on the line 3 4, Fig. 2.

Similar letters refer to similar parts throughout the several views.

A represents the journal of the axle, which is provided with the usual collar, *a*, and shoulder *b*, between which fits the brass bearing *B*, the latter being separated from the top of the box by the key *C*.

D is the exterior casing of the box, and is of a form similar or nearly similar to journal-boxes of the ordinary construction, there being in front the usual detachable door, *d*, to close the opening, through which the brass bearing *B*, key *C*, and other parts described hereinafter are introduced into the interior.

At the rear of the box, and concentric with

the axle *A*, is an annular flange or projection, *E*, which may be of different forms, but which we prefer to make beveled on the inside from the outer edge downward toward the interior of the box, as best observed on reference to Fig. 1.

F represents a portion of the car-wheel secured to the enlarged portion *e* of the axle *A*, and on the hub of the wheel are two annular flanges, *G* and *H*, the inner flange, *G*, projecting into the space between the flange *E* and the axle, and the outer flange, *H*, overhanging the said flange *E*, with which, however, both the flanges *G* and *H* are free from contact.

The flange *G* may be of different forms, but we prefer to make it of the peculiar form illustrated in Fig. 1 of the drawings—namely, beveled on the inside *f*, as well as on the exterior *g*.

A partition, *i*, divides the interior of the box into an upper compartment and lower compartment, *L*, the latter of which we term the "oil-chamber," and in this partition is an opening for the reception of a portion of the frame *J* in recesses, in which turn the journals of the roller *K*, the periphery of the latter running in the oil contained in the chamber *L*.

The frame *J* has at one end two projections, *i i*, which rest on the partition *I*, and at the opposite end a projection, *j*, against the under side of which bears the short arm of the lever *M*. (Shown by dotted lines in Fig. 2.) The fulcrum of this lever consists of a projection, *m*, bearing on the top of the partition *I*, and the long arm of the lever is made so heavy that it tends to raise the short arm, and with it one end of the frame, thereby maintaining the periphery of the oiling-roller *K* in constant contact with the journal of the axle.

It will be observed that there are no pins, screws, or other fastenings for maintaining the lever *M*, frame *J*, and oiling-roller *K* in their proper positions, the lever *M* occupying a chamber between the front of the box and a rib, *n*, formed within the same, and the frame being confined in its proper position by the said rib *n* and another rib, *q*, and by the opening in the partition *I* within which the frame fits, while the journals of the roller *K* have no tendency to escape from the recesses of the frame.

The advantages of our improvements may be described as follows:

First. Rollers have been heretofore used in journal-boxes for conveying oil to the journals, but have been maintained in contact with the latter by means of springs, which not only become clogged with the lubricating material, and more or less deteriorated and inefficient, but are difficult of application. In our improvements the oiling-roller is maintained in constant contact with the journal by the long weighted arm of the lever M acting on the rocking frame J, both the latter—the lever and the roller—being simply deposited in the box without the necessity of any elaborate fitting or adjustment, and always remaining in a condition to perform their duties.

Secondly. The partition I tends to maintain the oil within the chamber L, and to prevent that agitation of the oil which results in great waste of that lubricating material.

Thirdly. Whatever superfluous oil may be conveyed to the bearing by the oiling-roller and adheres to the axle will, on reaching the point α , where the annular beveled flange G meets the axle, follow the inclined interior f of the flange, and by centrifugal action be directed to the edge of the same, and consequently be restored to the interior of the box above the partition I, flowing thence through an opening in the rib g , and past the frame J into the chamber L.

Fourthly. The annular flange H on the hub of the car-wheel, overhanging the flange E of the box, owing to the speed with which it revolves, repels the dust and sand which would otherwise gain access to the interior of the box.

Although we have illustrated and described the annular flanges G and H as forming a part of the hub of the car-wheel, it will be evident that they may be separate from the same and secured to the axle.

We claim as our invention, and desire to secure by Letters Patent—

1. The oiling-roller K, frame J, and weighted lever M or its equivalent, the whole being constructed and arranged within a journal-box, and operating substantially as and for the purpose herein set forth.

2. The partition I, oil-chamber L, frame J, and oiling-roller K, the whole being arranged substantially as set forth, for the purpose specified.

3. The annular flange G or its equivalent, secured to or forming part of the wheel or axle, and arranged to project into the interior of the box, substantially as and for the purpose described.

4. The annular flange H, secured to or forming a part of the wheel or axle, and arranged in respect to the annular flange E of the box, substantially as and for the purpose herein set forth.

In testimony whereof we have signed our names to this specification in the presence of two subscribing witnesses.

O. BEECHER.
R. E. ROGERS.
